(57) **CLAIM**

The ornamental design for a foldable snorkel, as shown and described.

DESCRIPTION

FIG. 1 is a front elevational view of a foldable snorkel showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front side elevation view in folded state; and,

FIG. 10 is another perspective view in folded state.

The broken lines illustrate portions of the foldable snorkel that form no part of the claimed design.

1 Claim, 10 Drawing Sheets
